REACTANCE TUBE SYSTEM

Walter van B. Roberts, Princeton, N. J., assignor
to Radio Corporation of America, a corporation of Delaware

Application January 28, 1943, Serial No. 474,513

15 Claims. (CL 250—40)

This application relates to a reactance tube circuit substantially free of resistance component, which reactance may be used, for example, to control the frequency of an oscillator or oscillation circuit over a wide range. In one modification an effective negative inductance is provided while in another modification an effective negative capacity is provided, both free of resistive components. In a third modification both the above effects are provided simultaneously by the use of a complementary circuit which, in some aspects, resembles a push-pull circuit, and are used to control the frequency of an oscillation generator or oscillation circuit. The effective reactances provided in all of the modifications may be used in the phase shifting circuit of a reactance tube modulator or modulators associated with an oscillation circuit.

The oscillations generated by the oscillator or flowing in the circuit may be controlled as to phase or frequency or modified forms of either or both, or may be controlled in accordance with potentials which vary with slow changes in the mean frequency of generated oscillations or wave energy combined therewith, in the manner commonly referred to as automatic frequency control.

In describing my invention reference will be made to the attached drawings, wherein

Figure 1 illustrates somewhat schematically an oscillation circuit, a negative capacity substantially free of resistance, including a tube coupled to the oscillation circuit and a reactance tube in circuit with the first tube and with the oscillation circuit for controlling the tuning of the said oscillation circuit.

Figure 2 illustrates a modification of the arrangement of Figure 1. The modification of Figure 2 includes with the negative capacity a negative inductance, the capacity and inductance being associated with a reactance tube, which, in turn, is connected with a tuned circuit to control the tuning thereof.

Figure 3 illustrates a modification of the arrangement of Figure 2. In Figure 3 independent bias circuits are provided for the tubes providing the negative reactance effects and the reactance tubes, there being a reactance tube for each negative reactance, whereas in Figure 2 a single reactance tube is used.

Figures 3a and 3b are modifications of the arrangement of Figure 3.

Figure 4 is a simplified diagram used in describing the operation of the arrangement of Figure 3.

In Figure 1, 10 represents a tank circuit, such as, for example, the tuned circuit of an oscillator or of a high frequency relaying tube. The tank circuit includes a tuning condenser C and is connected at its high potential end by a small condenser C1 to the control grid G1 of a first tube 14 and also to the anode of a second tube 16. The cathodes of both tubes are connected to the low potential end of the tank circuit 10. The grid G1 of tube 14 is connected to the low potential point by condenser C2. The anode of tube 14 is coupled by inductance L and resistance r and coupling condenser 20 to the grid G2 of tube 16. The cathodes of tubes 14 and 16 are coupled by biasing circuits to ground. Control voltages may be supplied to G1 or G2 or both by way of grid leak resistances 22 and 24. As described later a reactive effect is developed in tube 16 and this reactive effect being in the circuit 10 by virtue of the coupling of the output electrodes of tube 16 across 10 determines the tuning thereof and thereby controls the frequency of the oscillations therein.

If E is the R. M. S. voltage across the circuit 10, the grid G1 of the first tube receives

$$\frac{EZ1Z2}{Z1+Z2} \frac{1}{Z1} \text{ volts}$$

where Z1 is the impedance of C1 and Z2 is the impedance of C2 and conductance σ of resistance 22 in parallel. This grid voltage may be written

$$\frac{jE\omega C1}{\sigma + j\omega C2 + j\omega C1}$$

35 The plate current of the first tube 14 is $g1$ times the grid voltage and flows through impedance $r + j\omega L$ so that the grid voltage of the second tube is

$$-jE\omega C1g1 \frac{r + j\omega L}{\sigma + j\omega(C2 + C1)}$$

If now we choose

$$r/\sigma = \frac{L}{C1 + C2}$$

40 45 the current drawn by the second tube 16 from the tank becomes simply

$$-jE\omega C1g1g2 \frac{L}{C1 + C2}$$

so that the tube 16 acts like a negative capacity of value

$$\frac{LC1}{(C1 + C2)} g1 g2$$

50 55 where $g1$ and $g2$ are the transconductances of the tubes 14 and 16 respectively.

In practice, the second tube 16 can put only a limited amount of alternating current so that the maximum volt-amperes of wattless current it can supply to the tank circuit 10 is the product of E and the maximum current output of the second tube 16. But the wattless volt-amperes in the oscillator tank per se is $E^2\omega C$ so that the greatest effect on the oscillation frequency will occur when E is chosen small (to permit the tube 14 acting as a large negative capacity while not drawing more than allowable current from the second tube 16) while C is chosen to just equal this negative capacity. In this case, the oscillation frequency can be swung from the natural frequency of the tank circuit 10 (when the control voltages brings $g_1 g_2$ to zero) up to a very high value when $g_1 g_2$ is maximum.

Referring to the circuit of Figure 1 in the analysis thereof given hereinbefore, it is seen that the tube 14 acts like a pure reactance, while if r is small ϵ is also small and in practice

C_1
 C_2

is very small so that the conductance across the tank 10 due to the circuit $C_1 C_2 \epsilon$ is very small.

The chief feature is that the voltage on the grid G_2 of the tube 16 is in exact quadrature with the tank 10 voltage at all frequencies. A subsidiary feature is that on account of the extra tube 14, and the fact that its grid voltage is nearly in phase with the tank voltage, there is very little conductance introduced across the tank circuit 10 by the grid excitation circuit $C_1 C_2 \epsilon$.

The control voltage may be applied to the grids of both tubes as shown, or in any proportion. Preferably it will be so proportioned that on the negative swing both tubes cut off at the same time, while on the positive swing both tubes attain maximum transconductance at the same time.

With the present circuit, the frequency can be swung from the natural frequency of the tank per se, up to a very high frequency, as the negative capacity of the tube system balances out the actual capacity across the tank coil.

In the modification of Figure 2 is provided either negative capacity or negative inductive susceptance according to the ratio of the control voltages on the tubes 14 and 14'. The tube 14 has its control grid G_1 connected between condenser C_1, C_2 . The tube 14' has its control grid G_1' connected between condensers C_1', C_2' so that both grids are excited by voltages of substantially the same phase from the high potential end of tank circuit 10. The modulating or controlling potentials are applied differentially by means of a transformer 30 between the control grids G_1 and G_1' . The anode of tube 14 is coupled by an inductive reactance designated by $+X$ and a coupling condenser 17 to the control grid G_2 of the reactance tube 16; while the anode of tube 14' is coupled by a capacitive reactance designated $-X$ and a coupling condenser 18 to the same control grid G_2 of tube 16.

One phase shifter produces output voltage

$$\frac{C_1}{C_1 + C_2} g_1(jX)$$

The other phase shifter produces output voltage

$$\frac{C_1}{C_1 + C_2} g_2(-jX)$$

These two voltages are combined through the small coupling condensers 17 and 18 on the grid

G_2 of the reactance tube 16, and the values of g_1 and g_2 are differentially modulated, as by push-pull grid control voltage input.

Analysis shows that the oscillation frequency can be reduced by the action of the lower tube to about the same extent as it can be increased by the upper tube.

The amount of frequency swing obtainable is determined by the ratio of wattless volt-amperes available from the reactance tube, to the geometric mean of the volt-amperes flowing in the physical coil and in the condenser of circuit 10 at the limit of the swing. This can be made large by operating the tank at low voltage and using a tank of large L/C ratio. The LC product, of course, determines the mean frequency, i. e., the frequency that occurs when $g_1 = g_2$ so that the reactance tube is not supplying any current.

The arrangement of Figure 3 makes use of the principle described hereinbefore. In Figure 3, however, I make use of two reactance tubes 16 and 16' having their control grids G_2 and G_2' coupled by coupling condensers to the anodes of the tubes 14 and 14' and to the secondary winding of a transformer T_2 in push-pull relation. The coupling between the control grid G_2 and the anode of tube 14 includes an inductance L and a resistance r_1 , while that between the grid G_2' and the anode of tube 14' includes a resistance r_2 and condenser K .

The grids G_1 and G_1' are connected to the secondary winding of a second transformer T_1 . The primary windings of the transformer T_1 and T_2 are in parallel and supplied with the desired modulating potentials from source 30.

Transformers T_1 , T_2 , and sources 32 and 36 provide one way to supply independently adjustable bias and differential modulation to the reactance tubes 16 and 16' and to the tubes 14 and 14'.

In each system, if there is any appreciable phase shift between grid voltage on G_1 (or G_1') and E , due to undesired effective conductance located as at ϵ_1 (or ϵ_2) this shift may be compensated by introduction of sufficient resistance r_1 (or r_2) with the result that the voltage on G_2 lags E by exactly 90° , while that on G_2' leads E by 90° over a wide range of applied frequencies.

It is necessary for this compensation that voltage for one grid, say G_1' , be tapped from an inductive voltage divider L_1, L_2 (here shown as the inductive branch of the oscillation tank) while the voltage for the other grid (G_1) be tapped from a capacitive divider C_1, C_2 (here acting also as capacitive branch of the oscillator tank). This can be proved as follows and in the explanation reference will be made to Figure 4.

Voltage at

$$G_1 = \frac{E}{Z_1} + \text{(admittance of elements } Z_1, Z_2, \text{ and } \epsilon \text{ considered as connected in parallel)}$$

Call this admittance y .

Voltage at

$$G_2 = \frac{E}{Z_1} \times \frac{Z_3}{y} \times gm$$

If now Z_1 is pure imaginary, then since gm , the tube transconductance, is real, the ratio Z_3/y must be real and independent of frequency for perfect quadrature voltage at G_2 .

In applying the foregoing analysis to the system of Figure 3, we see that in one case $Z_3 = r_1 + j\omega L$ so that for y to be of similar form we must have y

composed of a conductance σ_1 in parallel with pure capacities C_1 and C_2 so that

$$y = \sigma_1 + j\omega(C_1 - C_2)$$

Then if we choose

$$r_1/\sigma_1 = \frac{L}{C_1 + C_2}$$

the ratio Z_3/y is real.

On the other hand if

$$Z_3 = r_2 - \frac{j}{\omega K}$$

as is the case in the lower phase shifting system, then impedances Z_1 and Z_2 must be pure inductances so that the admittance of σ_2 in parallel with Z_1 and Z_2 will be of the form

$$\sigma_2 = \frac{j}{\omega(L_1 + L_2)}$$

in which case the ratio Z_3/y will obviously be real and constant if

$$r_2/\sigma_2 = \frac{L_1 + L_2}{K}$$

It should be emphasized that other networks are possible for deriving from E an input voltage for G_1 (or G_1') and that for any such network the desired 90° phase shift at the grid of G_2 (or G_2') may be obtained by suitable construction of the load circuit of the stage connecting G_1 to G_2 (or G_1' to G_2'). Furthermore, for many applications it is not important that the phase shift be exactly 90° over a wide range of frequencies, and it is within the scope of the present invention to deliberately employ networks which give a phase shift that departs from 90° somewhat, as a function of frequency, so as to introduce some regenerative component at frequencies where the amplitude of oscillation tends to fall off, or to introduce degeneration at frequencies of excess oscillation amplitude, or both.

In order to obtain the greatest possible frequency swing, the various circuit elements and voltages should be adjusted so that on one peak of the modulating voltage tube 16 is delivering the maximum volt-amperes of which it is capable, while $16'$ is delivering none. The oscillation frequency will then be a maximum. On the other peak of the modulation, tube 16 is cut off and tube $16'$ delivers maximum output and the frequency is a minimum. Without modulation input, the outputs of tubes 16 and $16'$ may be zero individually and in any case will be equal and of opposite phase so that the frequency of oscillation will be simply that of the tank itself.

While the system will operate with modulating voltage applied to either or both of the tubes in each system, and with a range of bias voltages, it is recommended that for any given installation a "cut-and-try" determination of the best bias and modulation input be employed.

For any given desired value of E , the radio frequency voltage applied to G_1 and the product of tube transconductance and impedance in its plate circuit should be chosen to cause maximum output from tube 16 at the peak of modulation voltage, if maximum frequency increase is to be obtained. The same remarks apply to tube $16'$ for greatest decrease of frequency.

The tube 26 is a generator of the regenerative type and generates the voltage flowing in the tuned circuit 10 .

The modification in Figure 3a is in many respects similar to the arrangement of Figure 3. In Figure 3a, however, a single reactance tube 16

is required and is used somewhat as in Figure 2. Modulation is applied to the grids G_1 and G_1' as in Figure 3 and may also be applied by way of switch S and transformer T_4 to the desired extent to the grid G_2 of tube 16 . If desired the modulation need not be applied to the grid G_2 in which case switch S is opened.

In the modification of Figure 3b the anodes of tubes 16 and $16'$ are coupled by an inductance L and a coupling condenser $17'$ to the grid G_2 of tube 16 . Modulation is applied to tubes 16 and $16'$ only with bias supplied by a variable source 23 . Radio frequency voltage from tank 10 is supplied from a capacity divider $C_1 C_2$ to the grid G_1 and an equal but conjugate phase radio voltage is supplied by inductance L_5 coupled to inductance L_3 to the grid G_1' of tube $16'$. Thus equal and substantially opposed radio frequency voltages are supplied to the grids G_1 and G_1' . The total current through L has therefore no component in quadrature with the tank voltage E so long as the transconductances of tubes 16 and $16'$ are equal, as is the case in the absence of modulation.

20 The term co-linear phase is believed to aptly designate voltages which may be either in phase or in phase opposition.

I claim:

1. In a system of the nature described, a tank circuit wherein wave energy the wave length of which is to be controlled appears, an electron discharge phase shifter tube having electrodes including an anode, a cathode, and a control grid, a reactance tube having electrodes including an anode, a cathode, and a control grid, a coupling between the cathodes of the tubes and the tank circuit, a connection for impressing voltage from the tank circuit in substantially co-linear phase, with respect to the phase of 40 the tank circuit voltage, on the control grid of said phase shifter tube, an output load of approximately pure reactance connected with the anode of said phase shifter tube, connections between said load and the control grid of the reactance tube for exciting said control grid by the voltage developed across said load of substantially pure reactance, means for establishing the desired phase relation between the voltage across said load and the voltage on the control grid of the phase shifter tube including a resistance connected to the anode of said phase shifter tube of a value sufficient to compensate 50 undesired effective conductance in connections to the control grid of the phase shifter tube, and a coupling between the anode and cathode of the reactance tube and the tank circuit.

2. A system as recited in claim 1 wherein said substantially pure reactance is inductive in character and said phase shifter tube simulates a negative capacity.

3. A system as recited in claim 1 wherein said substantially pure reactance is capacitive in character and wherein said phase shifter tube simulates a negative inductance.

4. In a system of the nature described, a tuned circuit wherein wave energy the wave length of which is to be controlled appears, an electron discharge phase shifter tube having electrodes including an anode, a cathode, and a control grid, a reactance tube having electrodes including an anode, a cathode, and a control grid, connections for impressing voltage from the tuned circuit in substantially co-linear phase on the control grid of said phase shifter tube, an output load of approximately pure reactance con-

nected with the anode of said phase shifter tube, connections between said load and the control grid of the reactance tube for exciting said control grid by the voltage developed across said load of substantially pure reactance, a resistance in the anode circuit of said first tube to compensate or offset departures of the impressed voltages from co-linearity over a wide range of frequencies, and a coupling between the anode and cathode of the reactance tube and the tank circuit.

5. A system as recited in claim 4 wherein said substantially pure reactance is inductive in character and said phase shifter tube simulates a negative capacity.

6. A system as recited in claim 4 wherein said substantially pure reactance is capacitive in character and said phase shifter tube simulates a negative inductance.

7. In a system of the nature described, a tank circuit wherein wave energy the wave length of which is to be controlled appears, a pair of electron discharge phase shifter tubes each having electrodes including an anode, a cathode, and a control grid, a pair of reactance tubes each having electrodes including an anode, a cathode, and a control grid, connections for impressing voltages from the tank circuit in substantially co-linear phase on the control grids of said phase shifter tubes, an output load of approximately pure reactance connected with the anode of each of said phase shifter tubes, said reactances being of opposite sign, connections between said loads and the control grids of the reactance tubes for exciting said control grids by the voltage developed across said loads of substantially pure reactance, and a coupling between the anodes and cathodes of the reactance tubes and the tank circuit.

8. A system as recited in claim 7 wherein one of said substantially pure reactances is capacitive in character, the other is inductive in character and one of said phase shifter tubes simulates a negative inductance while the other of said phase shifter tubes simulates a negative capacity.

9. In a system of the nature described, a tank circuit wherein wave energy the wave length of which is to be controlled flows, a pair of phase shifter tubes each having electrodes including a control grid, a cathode, and an anode, a reactance tube having input electrodes and having output electrodes coupled to said tank circuit, connections for applying voltage from the tank circuit substantially co-linearly on the control grids of said pair of phase shifter tubes, a load of substantially pure reactance connected with the anode of one of said phase shifter tubes, a load of substantially pure reactance of a sign opposite to the sign of said first reactance connected to the anode of the other of said phase shifter tubes, a coupling between said loads and the input electrodes of the reactance tube, and means for applying control potentials differentially to electrodes of said two phase shifter tubes.

10. In a system of the nature described, a tank circuit wherein wave energy the wave length of which is to be controlled flows, a pair of phase shifter tubes each having electrodes including a control grid, a cathode, and an anode, a pair of reactance tubes each having input electrodes and each having output electrodes coupled to said tank circuit, connections for applying voltage from the tank circuit substantially co-linearly on the control grids of said phase shifter tubes, a

load of substantially pure reactance connected with the anode of one of said phase shifter tubes, a load of substantially pure reactance of a sign opposite to the sign of said first reactance connected to the anode of the other of said phase shifter tubes, a coupling between said respective loads and the input electrodes of a different one of the reactance tubes, and means for applying control potentials differentially to electrodes of said two phase shifter tubes and to electrodes of said reactance tubes.

11. In a system of the nature described, a tank circuit wherein wave energy the wave length of which is to be controlled flows, a pair of tubes each having a control grid, a cathode, and an anode, a reactance tube having input and having output electrodes coupled across said tank circuit, connections for applying voltage from the tank circuit substantially co-linearly on the control grids of said pair of tubes, a load of substantially pure reactance connected with the anode of one tube of said pair of tubes, a load of substantially pure reactance of a sign opposite to the sign of said first reactance connected to the anode of the other tube of said pair of tubes, a coupling between said loads and the input electrodes of the reactance tube, and means for applying control potentials differentially to the input electrodes of at least two of said tubes.

12. In a system of the nature described, a tank circuit wherein wave energy the wave length of which is to be controlled appears, an electron discharge phase shifter tube having electrodes including an anode, a cathode and a control grid, a reactance tube having electrodes including an anode, a cathode and a control grid, a capacity potential divider including at least two capacities in shunt to said tank circuit, connections coupling the control grid and cathode of said phase shifter tube across at least one of said capacities of said capacity potential divider for impressing voltage from the tank circuit in substantially co-linear phase, with respect to the phase of the tank circuit voltage, on the control grid of the phase shifter tube, an output load of approximately pure reactance connected with the anode of said phase shifter tube, connections between said load and the control grid of the reactance tube for exciting said control grid by the voltage developed across said load of substantially pure reactance, a coupling between the cathode of said reactance tube and said tank circuit, and a coupling between the anode of said reactance tube and said tank circuit.

13. In a system of the nature described, a tank circuit wherein wave energy the wave length of which is to be controlled appears, an electron discharge phase shifter tube having electrodes including an anode, a cathode, and a control grid, a reactance tube having electrodes including an anode, a cathode, and a control grid, a coupling between the cathode of the reactance tube and the tank circuit, at least two reactances in shunt to said tank circuit, connections coupling the control grid and cathode of said phase shifter tube across at least one of said reactances for impressing voltage from the tank circuit in substantially co-linear phase, with respect to the phase of the tank circuit voltage, on the control grid of said phase shifter tube, the arrangement being such that the conductance across the tank circuit due to the said reactances in shunt thereto and connections to the control grid of the phase shifter tube is small, an out-

put load of approximately pure reactance connected with the anode of said phase shifter tube, connections between said load and the control grid of the reactance tube for exciting said control grid by the voltage developed across said load of substantially pure reactance, and a coupling between the anode and cathode of the reactance tube and the tank circuit.

14. An arrangement as recited in claim 1, wherein said tank circuit has a capacitive branch and an inductive branch and wherein said connection for impressing voltage from the tank

circuit in substantially co-linear phase on the control grid of the phase shifter tube is to the inductive branch of the tank circuit.

15. An arrangement as recited in claim 1, wherein said tank circuit has an inductive branch and a capacitive branch and wherein said connection for impressing voltage from the tank circuit in substantially co-linear phase on the control grid of the phase shifter tube is to the capacitive branch of the tank circuit.

WALTER VAN B. ROBERTS.
